Patented July 10, 1917.

UNITED STATES PATENT OFFICE.

EDWARD F. OLSON, OF BERLIN, NORTH DAKOTA.

WATCH.

1,232,962.

Specification of Letters Patent. Patented July 10, 1917.

Application filed October 27, 1916. Serial No. 128,085.

To all whom it may concern:

Be it known that I, EDWARD F. OLSON, a citizen of the United States, residing at Berlin, in the county of La Moure and State 5 of North Dakota, have invented new and useful Improvements in Watches, of which the following is a specification.

This invention relates to improvements in watches and more particularly to watches 10 in which provision is made for illuminating the watch dial.

The primary object of the invention is to provide a watch of this character having an incandescent bulb mounted in a socket 15 formed in the bezel of the watch and having connection with a source of electrical energy arranged beneath the cover on the back of the watch and controlled through the medium of a switch rotatably mounted 20 on the watch stem and by means of which the circuit between the source of energy and lamp may be closed to momentarily illuminate the dial of the watch.

Another object of the invention is to provide a switch of novel construction which 25 is mounted upon the winding stem housing of the watch in such a manner that communication may be established between the incandescent lamp and the source of electrical 30 energy by partially rotating the switch in either direction.

A further object of the invention is to provide the watch cover with novel means 35 for retaining therein the source of electrical energy for supplying the illuminating power for the lamp mounted within a socket formed in the bezel.

A still further object of the invention is to so construct the watch that the lamp and 40 electrical circuit connecting the same with the source of electrical energy will be substantially inclosed in the watch casing and protected from injury when the watch is inserted or removed from the pocket in 45 which it is carried.

With these and other objects in view, the invention resides in the novel combination and arrangement of parts, which will be hereinafter described and particularly 50 pointed out in the claim.

The preferred embodiment of the invention has been illustrated in the accompanying drawing, although no restriction is necessarily made to the precise details of construction therein shown, as changes, altera- 55

tions, and modifications, within the scope of the claim may be resorted to when desired.

Like characters of reference denote corresponding parts throughout the several views in the drawing, in which:

Figure 1 is a face view of a watch constructed in accordance with the invention.

Fig. 2 is a view of the watch showing the cover removed to more clearly illustrate the manner of connecting the source of electrical energy therewith.

Fig. 3 is a vertical transverse section on the line 3—3 of Fig. 1.

Fig. 4 is a detailed perspective view of the switch for closing the electrical circuit between the incandescent lamp on the watch dial and the source of electrical energy carried by the watch cover.

Referring now to the drawing in detail, the numeral 1 designates a watch of the type now in common use, the casing 2 of which is provided with the usual housing 3 in which is received the winding and setting stem having a crown 4, said housing having formed therein between its ends an annular groove 5 arranged adjacent an opening 6 in the casing 2, said opening receiving therein a plug of insulating material 7 having mounted therein a contact member 8 which extends exteriorly of the casing 2.

Mounted to turn in an annular groove 5 on the housing 3 is a switch 9, said switch being in the form of a ring which is held by the walls of the groove against longitudinal movement on the housing, said ring having arranged upon one face thereof spaced contact fingers 10 and 11, said fingers being normally held spaced from the contact member 8 through the medium of a spring 11, one terminal of which is connected with the housing at a point diametrically opposite the connection of the other terminal of the spring with the switch 9, said spring serving to hold the switch 9 firmly engaged with a wall of the groove to prevent casual turning of the switch upon the housing. When the switch is partially rotated upon the housing 3 to bring either of the contact fingers into engagement with the member 8, the spring upon the release of the pressure from the switch will restore the same to its normal position.

The casing 2 has arranged therein in advance of the watch mechanism a lettered dial 12 underlying the crystal 13 which is

connected with the casing 2 by a bezel 14 having formed therein a lamp socket 15 receiving an incandescent bulb 16 arranged between the numerals 12 and 1 on the dial 5 and between the dial and crystal 13.

The back of the casing 2 is closed by a cover 17 arranged upon the inner face of which are spaced spring arms 17' receiving therebetween and retaining upon the cover a 10 suitable source of electrical energy 18 such as a battery or the like, said battery being preferably circular in shape so that when the cover 17 is in closed position, the battery will lie wholly within the cover and in no 15 way interfere with the mechanism arranged within the casing 2.

Suitable conducting members for conveying the electrical energy from the battery 18 to the lamp 15 are arranged within the 20 casing 2 and designated by the numerals 19 and 20, the conductor 19 having a connection with the lamp 15 and a binding post on the battery 18 while the conductor 20 which is also connected with the battery 18 has one 25 end thereof passed through the plug 7 and secured to the contact member 8 thereon, thus enabling the electrical circuit to be closed when one of the contact fingers 10 on the switch 9 are brought into contact 30 with the member 8, so that the lamp 15 will be illuminated.

Through the above described arrangement of parts when it is desired to illuminate the lamp, the switch 9 which is normally held in

an open position by the spring 11 is turned 35 on the housing 3 until one of the fingers 10 is brought into contact with the member 8 at which time the current from the battery 18 may be used to energize the lamp 15 so that as long as the switch remains in a closed 40 position, the lamp will be illuminated and upon the release of the switch, the same will be moved to open position by the spring 11.

From the foregoing description, taken in connection with the accompanying drawing, 45 it is at once apparent that a watch has been provided in which the dial thereof may be momentarily illuminated when found desirable and with the illuminating mechanism so arranged with relation to the watch 50 casing that the said mechanism will be protected thereby.

Having thus described the invention, what is claimed as new, is:

A watch having a winding stem housing 55 having an annular groove therein, a ring mounted to turn in said groove, a spring engaged with said housing and ring normally holding said ring firmly engaged with a wall of the groove to prevent casual rotation of the ring, an electrical circuit in which said ring and housing are arranged including a contact plate extending exteriorly of the watch, and spaced fingers depending from the underside of said ring to 60 engage said contact when the ring is turned.

In testimony whereof I affix my signature.
EDWARD F. OLSON.
